UNITED STATES PATENT OFFICE.

ABRAHAM H. VANDLING, OF NORTHUMBERLAND, PENNSYLVANIA.

NAILLESS HORSESHOE.

1,183,609.

Specification of Letters Patent.

Patented May 16, 1916.

Application filed March 18, 1916. Serial No. 85,031.

To all whom it may concern:

Be it known that I, ABRAHAM H. VANDLING, a citizen of the United States, residing at Northumberland, in the county of Northumberland, State of Pennsylvania, have 5 invented a new and useful Nailless Horseshoe; and I do hereby declare the following to be a full, clear, and exact description of the invention, such as will enable others 10 skilled in the art to which it appertains to make and use the same.

The present invention relates to certain new and useful improvements in horseshoes, and has for its object to provide a device of 15 this character which embodies novel features of construction whereby it can be applied to the foot of the animal without the use of the customary nails.

Further objects of the invention are to 20 provide a nailless horseshoe which is comparatively simple and inexpensive in its construction, which can be readily placed in position or removed therefrom, which will firmly and securely grip the foot of the animal, and which is formed in sections constructed to interlock with each other in such a manner as to make relative movement impossible when the device is in operative position.

With these and other objects in view, the 30 invention consists in certain novel combinations and arrangements of the parts as will more fully appear as the description proceeds, the novel features thereof being 35 pointed out in the appended claims.

For a full understanding of the invention, reference is to be had to the following description and accompanying drawing, in which:—

40 Figure 1 is a top plan view of a nailless horseshoe constructed in accordance with the invention. Fig. 2 is a side elevation thereof. Fig. 3 is a front elevation of the same. Fig. 4 is a transverse sectional view 45 taken on the line 4—4 of Fig. 1 and looking in the direction of the arrows. Fig. 5 is a fragmentary top plan view with portions broken away and shown in section to more clearly illustrate the details of construction. 50 Fig. 6 is a top plan view of a modified form of the invention. Fig. 7 is a fragmentary side elevation of the same.

Corresponding and like parts are referred to in the following description and indicated 55 in all the views of the drawings by the same reference characters.

Referring to the drawings, the reference character A designates a horseshoe which is divided at the middle of the toe thereof to provide the two complementary sections 1 and 2. These sections 1 and 2 are provided both at the toe and the heel of the shoe with upwardly projecting and inwardly inclined hoof engaging flanges 3, said flanges being of a size to obtain a sufficient bearing upon the horse's hoof, and being inclined inwardly in such a manner as to securely grip the same when in operative position. The transverse toe culk which projects downwardly from the toe of the shoe is formed in the sections 4^a and 4^b formed in connection with the respective halves 1 and 2 of the shoe. The section 4^a of the toe culk is formed with a beveled end 5 which is overlapped by a tongue 6 upon the culk section 4^b, the lower face of the tongue being beveled to fit tightly against the beveled end 5 of the culk section 4^a. The rear ends of the complementary shoe sections 1 and 2 are provided with the usual heel calks 7.

The sections 1 and 2 of the shoe are hingedly connected at the toe so that they can be swung apart when placing the shoe in position or removing it therefrom. For this purpose the extreme forward end of the section 2 is formed with a laterally projecting ear 8 which is hingedly connected at 9 to a pivot ear 10 on the section 1. The meeting end of the section 2 is also formed with a longitudinal rib 11 which is adapted to be received within a longitudinal groove 12 in the meeting edge of the section 1. A stud 13 projects from the base of the groove 11 at an intermediate point in the length thereof so as to be received within a notch 14 in the rib 11 when the parts are in operative position. It will thus be obvious that when the two halves or sections 1 and 2 of the horseshoe are swung toward each other to bring them into operative position, the rib 11 will enter the groove 12 while the stud 13 will enter the notch 14, thereby producing an interlocking connection between the sections which holds them securely against vertical or longitudinal movement relative to each other. In this manner the strain upon the hinge connection is greatly reduced.

Projecting rearwardly from the heel ends of the shoe sections 1 and 2 are the eyes 15 which receive a transverse securing bolt 16. The bolt 16 is threaded at 17 in one of the

eyes 15 and after the parts have been assembled this bolt is tightened to forcibly draw the sections 1 and 2 of the horseshoe toward each other and clamp the horseshoe in operative position upon the hoof of the animal. A coil spring 18 is preferably applied to the bolt 16 and interposed between the head thereof and the adjacent eye 15, so that the parts are held yieldingly in position and the foot of the animal can expand if necessary.

A slight modification is illustrated by Fig. 7, in which a slightly different form of hinge connection is provided between the horseshoe sections 1 and 2, although in all other respects the construction is identical with that previously described. A hooked tongue 19 is substituted for the pivot ear 8, said tongue projecting forwardly from the section 2 and being adapted to engage a looped keeper 20 projecting from the section 1. The two parts can thus be entirely disconnected and separated when they are swung apart, although they are held in proper position when applied to the hoof of the draft animal. The manner of applying and using the modified construction is identical with that previously described.

Having thus described the invention, what I claim as new and desire to secure by Letters Patent, is:—

1. A nailless horseshoe divided at the toe to provide complemental sections and provided with hoof engaging flanges, said complemental sections being hingedly connected and the meeting face of one being formed with a longitudinal rib with a notch therein, while the meeting face of the other is formed with a longitudinal groove to receive the rib and a stud projecting from the base of the groove to enter the notch of the

rib, and a transverse clamping bolt connecting the heel ends of the shoe sections.

2. A nailless horseshoe divided at the toe to provide complemental sections and provided with hoof engaging flanges, said complemental sections being hingedly connected and provided at their meeting faces with corresponding projections and depressions arranged to produce an interlocking connection, a transverse toe talk part on one shoe section and part on the other shoe section, one part of the toe talk being formed with an extension overhanging the other part of the toe talk, and a transverse clamping bolt connecting the heel ends of the shoe sections.

3. A nailless horseshoe divided at the toe thereof to provide complemental sections and formed with hoof engaging flanges, said complemental sections being hingedly connected and the meeting face of one section being formed with a longitudinal rib having a notch therein, while the meeting face of the other section is formed with a longitudinal groove adapted to receive the before mentioned rib and with a stud projecting from the base of the groove to enter the notch of the rib, a transverse toe talk having part thereof on one shoe section and part on the other shoe section, one part of the toe talk being formed with an extension overhanging the other part of the toe talk, and a transverse clamping bolt connecting the heel ends of the shoe sections.

In testimony whereof I have signed my name to this specification in the presence of two subscribing witnesses.

ABRAHAM H. VANDLING.
